CHAIR

Hiram N. McLellan, Shaker Heights, Ohio, and Gustav C. Balbach, Grand Rapids, Mich., assignors to The Taylor Chair Company, Bedford, Ohio, a corporation of Ohio

Application April 27, 1936, Serial No. 76,502

4 Claims. (Cl. 155—196)

This invention relates to a chair construction and has for its principal object to provide a construction wherein the chair seat and legs are joined in a simple manner making for greater 5 rigidity and strength. A further object is to provide a leg bracing construction peculiarly adapted for attachment of a chair leg to a seat construction comprising a seat element having a skirting extending therearound and to provide at the same time a very effective joint for 10 holding the right angularly extending portions of the skirting together and holding the leg in place.

Other objects will be in part apparent and in 15 part pointed out hereinafter in connection with the accompanying drawing wherein Fig. 1 is a side elevation of a chair embodying the new construction; Fig. 2 is a bottom plan section corresponding substantially to the line 2—2 of 20 Fig. 1; Fig. 3 is a section on the line 3—3 of Fig. 2; Fig. 4 is a section on the line 4—4 of Fig. 2; Fig. 5 is a section on the line 5—5 of Fig. 2; Fig. 6 is a diagrammatic, fragmentary section showing a different form of skirting attached to the chair seat.

In the drawing the numeral 10 indicates generally a chair seat having attached thereto a back rest 11 of any suitable construction and supporting legs 12. The legs 12 may be braced 30 below the chair seat in any conventional manner, as by rungs 13.

The chair seat 10 may comprise an upper seat element 14 to which may be secured a suitable continuous skirting 15 as by screws 16 extending 35 upwardly through the skirting into the chair seat element 14. The skirting 15 is made up of a U-shaped portion 17, the legs of which make right angles with the front skirting portion 18. In the angles between the portions 17 and 18 40 and having an interfitting rib connection with each thereof are blocks 19. The interfitting rib connection comprises complementary rib formations in the skirting portions 17 and 18 and blocks 19 as will be clear from Fig. 4. After the 45 skirting and blocks are formed as shown, the contacting surfaces may be coated with adhesive and pressed together.

At the curved skirting portions forming the junctions of the bight and legs thereof, we provide ribbed portions 20 to which complementary ribbed blocks 21 are secured.

After the skirting and blocks 19 and 21 are assembled, we provide vertical bores 22 intersecting the blocks and the adjacent skirting portions. Preferably these bores are mostly with-

in the blocks 19 and 21 and intersect the skirting only to a slight extent, suitably about the depth of the rib grooves. They may intersect the skirting to a somewhat greater extent but it is desirable not to weaken the same very 5 much. It is, however, highly desirable that the bores 22 should intersect the skirting to some extent so as to secure a firm bonding of the cylindrical projections 23 of the legs 12 not only to the blocks 19 and 21 but to the skirting as 10 well. The legs 12 are provided with shoulders 24 surrounding the projections 23 and abutting the lower surfaces of the skirting members 17 and 18. Screws 25 may be inserted through the blocks 19 into the projections 23.

As will be clear from Fig. 4 the skirting 15 in the preferred form described above simply abuts the lower surface of the chair seat 14. In Fig. 6 we have shown a modified form wherein the skirting 15^a is provided with an upstanding flange 15^b forming a socket for receiving the seat portion 14^a.

From the foregoing, it will be obvious that we have provided a chair construction well adapted for its intended purposes and while we have shown and described the present preferred embodiment of our invention, we are aware that the same may be realized in varying structures and we therefore do not wish to be limited to the details of the disclosures but only in accordance with the appended claims and the prior art.

Having thus described our invention, what we claim is:

1. In a chair construction, a seat, a continuous skirting rigidly secured to the under side thereof and including side and front portions forming an angle with each other, a corner block in an angle between said skirting portions, there being an interfitting rib connection between said block and each of said portions, a vertical bore intersecting said block and each of said portions and a leg having a projection received in said bore and a shoulder surrounding said projection and engaging the bottom of said skirting.

2. In a chair construction, a seat, a continuous skirting rigidly secured to the under side thereof and including side and front portions forming an angle with each other, a corner block in an angle between said skirting portions, there being an interfitting rib connection between said block and said skirting, a vertical bore intersecting said block and each of said portions and a leg having a projection received

in said bore and a shoulder surrounding said projection and engaging the bottom of the skirting.

3. In a chair construction, a seat, a continuous skirting rigidly secured to the under side thereof and including side and front portions forming an angle with each other, a corner block in an angle between said skirting portions, there being an interfitting rib connection between said block and each of said portions, a vertical bore intersecting said block and each of said portions and a leg having a projection received in said bore and a shoulder surrounding said projection and engaging the bottom of said skirting, said rib connection including al-

ternating ribs and grooves of such depth that said block embraces 180° of said projection.

4. In a chair construction, a seat, a continuous skirting rigidly secured to the under side thereof and including side and front portions forming an angle with each other, a corner block in an angle between said skirting portions, there being an interfitting rib connection between said block and said skirting, a vertical bore intersecting said block, and a leg having a projection received in said bore and a shoulder surrounding said projection and engaging the bottom of the skirting.
